UNITED STATES PATENT OFFICE.

HENRY HORAN, OF EAST ORANGE, NEW JERSEY, ASSIGNOR TO HARTFORD CARPET COMPANY, OF HARTFORD, CONNECTICUT.

DESIGN FOR CARPET.

Specification forming part of Design No. 11,408, dated September 9, 1879; application filed August 2, 1879.
[Term of patent 3½ years.]

To all whom it may concern:

Be it known that I, HENRY HORAN, of East Orange, in the county of Essex and State of New Jersey, have invented a new and original Design for a Carpet, of which the following is a specification.

The accompanying photograph illustrates my new design.

This invention relates to a new design for carpets, oil-cloths, and analogous fabrics; and consists in the novel grouping and configuration of figures hereinafter more fully pointed out.

Four obliquely-placed rectangles, A, A', B, and B', meet at the corners and form a fifth rectangle, C, between them. The figures A and A' are alike; the figure B is like the figure B'. Between the figures A and B is a rectangle, D; between the figures A and B', an obliquely-placed rectangle, E; between the figures A' and B', a nearly rectangular figure, F; and between the figures A' and B, an irregular figure, resembling an octagon, G.

The figures A, B, and C have geometrical

backgrounds of peculiar patterns. Groups of flowers and leaves are scattered over the entire carpet, as shown.

The design is based upon that shown in Letters Patent No. 11,061, dated March 11, 1879, and differs from the same more particularly in the character of the groundwork of the figures B B', in the fact that said groundwork comes in positive contact with the adjoining background, as does also that of the figures A and A', and also in the novel ornamentation of the figure F, whose lower triangular field contains two small squares.

I claim—

The design for a carpet, consisting of the figures A, B, C, D, E, F, and G, having the floral and geometrical ornaments placed therein, substantially as shown.

The above specification of my invention signed by me this 30th day of July, 1879.

HENRY HORAN.
